Primary Examiner — Omeed Agilee*Assistant Examiner* — David Truong(74) *Attorney, Agent, or Firm* — The Belles Group, P.C.(57) **CLAIM**

The ornamental design for a bottle, as shown and described.

DESCRIPTIONFIG. 1 is a top perspective view of a bottle showing my new design;
FIG. 2 is bottom perspective view thereof;
FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines illustrating portions of the bottle form no part of the claimed design.

1 Claim, 8 Drawing Sheets(56)
